D. McNAIR.

CARPET.

No. 15,249.

Patented Aug. 12, 1884.

UNITED STATES PATENT OFFICE.

DAVID MCNAIR, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 15,249, dated August 12, 1884.

Application filed May 13, 1884. Term of patent 3½ years.

To all whom it may concern:

Be it known that I, DAVID MCNAIR, of Boston, in the county of Suffolk and State of Massachusetts, have invented a new and original 5 Design for Carpets, of which the following is a specification.

The nature of my design is fully shown in the accompanying photographic illustration.

The design is composed of the floral and 10 foliage ornamentation, arranged, as shown, in curved vines and stems.

I am aware of Design Patent to T. J. Stearns, No. 11,147, dated April 18, 1879, showing leaves and flowers thickly arranged, but not connected by curved vines extending through the 15

pattern, as in my design. The form of the leaves and flowers in my design also differs from the form of the leaves and flowers in Stearns' design.

I claim—

The design for a carpet, substantially as shown and described.

In testimony whereof I have signed my name to this specification, in the presence of two subscribing witnesses, this 5th day of May, 1884.

DAVID MCNAIR.

Witnesses:

DAVID G. MELVILLE,
THOMAS J. STEARNS.
